ATTORNEY

UNITED STATES PATENT OFFICE.

ALFRED SPRINGER, OF CINCINNATI, OHIO.

MOLECULAR PIVOT-BALANCE.

SPECIFICATION forming part of Letters Patent No. 340,011, dated April 13, 1896.

Application filed April 27, 1885. Serial No. 163,511. (No model.)

To all whom it may concern:

Be it known that I, ALFRED SPRINGER, a citizen of the United States, residing at Cincinnati, Ohio, have invented new and useful improvements in Molecular Pivot-Balances, of which the following is a specification.

My invention relates to that class of balances in which one or more leverage multipliers are used, and is especially applicable to those in which the fulcrum-pivot is composed of elastic strips, bands, wires, &c., acting torsionally or flexionally. The load upon the scale-beam tends, obviously, to depress the axis of the beam, and where an elastic pivot is employed, as in the case of torsion-balances, it tends to "sag" the pivot also. As this acts only upon the beam and does not affect the independent fulcrum of the auxiliary lever or levers, its effect is to impair the proper relation of the main beam to its connected lever or levers and introduce a serious error in the readings of the marking-lever, which error increases with the amount of load.

The object of my invention is to provide a remedy for this difficulty, whereby the effect of the depression of the main beam or its pivot may be counteracted and the scale-readings remain unimpaired.

My invention will be more clearly apprehended by reference to the accompanying drawings, in which Figure 1 is a perspective view of a simple beam-scale to which the auxiliary beam or lever is attached for scale-reading. Fig. 2 is a diagram of the same scale, showing the relation of the levers and their pivotal connections. Fig. 3 is a diagram representing a torsional pivot stretched between its holding-abutments, with cross-section of the scale-beam attached thereto and indicating the sagging effect of weight upon the beam. Fig. 4 is a diagram in the plane of the main and auxiliary beams, showing the abnormal deflection of the auxiliary beam or pointer due to the abnormal depression of the main beam. Fig. 5 is a diagram of the same parts, showing the effect of the same as corrected by my improvement. Fig. 6 is a detailed side view and cross-section of the adjusting mechanism for shifting the distance of the terminal pivot from the center of rotation upon the main beam.

Referring now to the drawings, A represents the main scale-beam; B, the supporting-ped-

estal; b b, the abutments between which the fulcrum-pivot is stretched; P, the fulcrum-pivot; E E, the terminal torsion-frames, 55 (embodying torsional pivots $p^1 p^2$), by which the scale-pans FF are suspended; C, the auxiliary lever, used as an indicating-pointer and moving upon the graduated arc-plate D; E', the torsion-frame connecting the main beam 60 with the auxiliary beam, including the torsion-pivots p^3 and p^4 , and E' represents the torsion-frame embodying the torsion-pivot p^4 , constituting the fulcrum of the auxiliary lever or pointer C. The torsion-frame E' is mounted 65 upon or hung from suitable supports, f f, attached to the general frame or containing-case of the balance. The scale-beam A is provided with a central standard, S, and an adjustable weight, W, serving as a counterpoise to the 70 molecular resistance of the pivots, and the auxiliary beam C is also furnished with a vertical standard, s, rising above its fulcrum-pivot, and an adjustable weight, w, acting in conjunction with the counterpoise W. The 75 construction of the scale as thus shown is fully detailed in other patents already granted to me and in applications now pending, and need not be further described here.

The difficulty to which my present invention 80 is directed is partially illustrated in Fig. 3, in which it will be obvious that a weight placed upon the beam A—that is, a load placed in the scale-pans of the beam—tends to stretch the fulcrum-pivot and depress it and the beam 85 into the positions indicated by dotted lines, the effect of which upon the lever C is indicated in Fig. 4. The scale-beam A, as shown in said figure, being depressed into the position indicated by dotted lines, the auxiliary lever or pointer C will be drawn down into the diagonal position, also indicated by dotted lines, and the arc which would in such case be traversed by the pointer C represents the amount of error upon the graduated arc-plate 90 D. This error I overcome by increasing the length of the beam from its fulcrum to the end opposite the secondary lever-connection—that is, at the right-hand end indicated in the drawings—the effect of which is to increase the 95 statical moment of the weight placed at or suspended from such end, thereby tending to elevate the opposite end of the beam just sufficiently to overcome the tendency referred to.

Thus, referring to Fig. 5, the fulcrum-pivot *P* being depressed to the position indicated in the dotted lines, instead of remaining parallel to its former position, is thrown into the 5 inclined position shown by the dotted lines, in which the left-hand end of the beam is elevated just sufficiently to counteract the effect of the change of position of the fulcrum.

In carrying out my invention mechanically, 10 it may obviously be applied in all classes of balances, whatever may be their construction, and also by various means adapted to each particular case.

In order to secure the necessary elongation 15 of the beam, as described, I have found it convenient to use the device indicated in Fig. 6, in which the terminal pivot *p'* is passed through and secured in a sliding block *i*, secured beneath and around the beam, having an upward 20 projection, *i'*, threaded upon an adjusting-screw, *h*, passing through lugs *g g*, arranged upon the upper side of the beam. By means of an adjusting device of this nature the beam may be properly lengthened after construction 25 as part of the general adjustment of the balance, and it is found that when so made, in proper relation to the elastic strength of the pivot as against vertical deflection, the proportionate increase in the statical moment of 30 the weight or load maintains a constant and uniform correspondence with the vertical deflection of the pivot, and the scale action is perfect for all loads within its predetermined capacity.

35 The temporary adjustability of the length of the beam is a matter of convenience merely, and the length may be permanently fixed in the original construction, if preferred. In steelyard-balances the result is attained in the 40 same manner by adding to the length of the beam at the load-suspension end, so as to render the "fulcrum length" slightly in excess

of the unit of leverage multiplication. The same result may be attained by shifting the position of the fulcrum-pivot, and such is 45 within the spirit of my invention, but is far less convenient practically.

I claim as my invention, and desire to secure by Letters Patent of the United States—

1. In a molecular pivot-balance embodying 50 one or more leverage multiplications, the combination, with the balance-beam lengthened at its load-suspension end beyond the normal unit of leverage multiplication, of an auxiliary multiplying beam or marker independently 55 fulcrumed and connected with the main beam by a torsional frame, substantially as described.

2. In a molecular pivot-balance, the combination of a balance-beam having a torsional fulcrum, an auxiliary multiplying beam or 60 marker independently fulcrumed, a torsional pivot-connection between said beams, and a horizontally adjustable weight-support upon the balance-beam at the end opposite its connection with the auxiliary beam, substantially 65 as described.

3. In a molecular pivot-balance, the combination of the main beam *A*, the independently-fulcrumed beam or marker *C*, the connecting-frame *E*, having torsional pivots *p² p³*, the 70 terminal torsion-frames *E E*, and the horizontally-sliding block *i*, for adjustably connecting one of said terminal frames to the end of the main beam opposite its torsional connection with the marker, substantially as described.

In testimony whereof I have hereunto set my hand in the presence of two subscribing witnesses.

ALFRED SPRINGER.
